SMOKING PIPE

Lincoln T. Young, Lynwood, Calif.

Application November 30, 1943, Serial No. 512,357

1 Claim (Cl. 131—184)

This invention relates to a smoking pipe.

An object of the invention is to improve pipe smoking pleasure by minimizing the possibility of the pipe stem from being clogged up at any time—either when filling the bowl or while smoking.

Another object of the invention is the provision of simple and efficient means whereby a vacant space is formed between the tobacco in the bowl of the pipe and the stem thereof, resulting in a great amount of smoking pleasure.

A still further object of the invention is the construction of a simple and efficient stopper device that can be applied to many different styles or constructions of pipes, whereby a vaulted condition of the packed tobacco in the bowl will result in a highly efficient smoking, by the user of the pipe.

With the foregoing and other objects in view, my invention comprises certain novel constructions, combinations, and arrangements of parts as will be hereinafter fully described, illustrated in the accompanying drawing, and more particularly pointed out in the appended claim.

In the drawing:

Figure 1 is a view partly in elevation and partly in vertical section of a pipe constructed in accordance with the present invention, showing the stopper device in an elevated or operating position, while

Figure 2 is a similar view of a pipe, showing the stopper device at rest or in an inoperative position.

Figure 3 is a vertical fragmentary sectional view of the pipe showing another embodiment of the present invention.

Referring to the drawing by numerals, in Figs. 1 and 2, showing the preferred embodiment of the invention, 1 designates a bowl and 2 the stem of a pipe of any ordinary construction. The usual passage 3 is in the stem 2. In the bottom of the bowl 1 is a substantially cup-shaped casing 4 in one side of which is an aperture 5 communicating with the passage 3. A stopper device 6 is slidably mounted upon the casing 4 and comprises a vertical shaft 7 that extends through the bottom of the casing 4. Fixedly secured to the outer or lower end of shaft 7 is a disc grip 8. Fixedly secured to the inner or upper end of shaft 7 is a head 9, the top of which head is rounded or convexed for the purpose hereinafter described.

In the embodiment shown in Figure 3, the casing 4a is provided with the aperture 5 in communication with the passage 3 of stem 2, and under aperture 5 is a second aperture 5a through

which extends a lever 10 that is pivotally mounted at 11 upon the pipe. Pivotally connected to the inner end of lever 10 is a link 12; the upper end of link 12 is pivotally connected to the head 9. The lever 10 is normally seated in the elongated slot 13, but upon the operator grasping or contacting the depending grip 14, he can swing the outer end of the lever downward as shown by dotted line "A," causing the head to rise or be shoved upwardly within casing 4a to the position shown in dotted lines in Figure 3, while the tobacco is being placed within the bowl 1.

When filling the bowl with tobacco the head 9 is held in the closed position shown in Figure 1. During this filling operation, the tobacco becomes compressed against the head so that it will remain in a vaulted position, as shown in Figures 2 and 3, and then the stopper device is operated to cause the head to move to its rest or inoperative position (Figs. 2 and 3) which is the smoking position. Thus, it will be seen that no tobacco can get to the stem to clog it during the filling process.

With pipes in general it is pretty much of a gamble whether or not one is going to get a smoke without some extra effort. Ofttimes after filling a pipe and before being able to light it, one is obliged to remove all the tobacco and try again, or resort to the use of some special tool to effect a passage for draft; this is entirely eliminated by my invention, because the stem is free and ready for use.

When the stem of many makes of pipe does become clogged, extra effort is required to draw smoke through. This results in not only drawing a certain amount of smoke through, but the smoke is often accompanied by disagreeable solids and condensates, which enhance the "bite." This condition is next to impossible with a pipe embodying my invention, because the large, free under-surface of the tobacco fill and the unrestricted passage through the stem permits such exceptionally easy drawing that it requires little or no effort. This obviously results in a continuously smooth and uniform smoking process.

The tobacco in the bowl lights more readily and burns more uniformly to the side of the bowl. This is due to the position of the chamber which causes a direct vertical draft through the tobacco.

The pipe bowl 1 may be cleaned or reamed with the stopper device in a closed position, thus insuring against any "cleanings" finding their way to the stem.

From actual experience of smoking my improved pipe, I can say that from the first puff there is a distinct and noticeable improvement,

and as the smoking continues the improvement will become more and more appreciated.

While I have described the preferred embodiments of my invention and illustrated the same in the accompanying drawing, certain minor changes or alterations may appear to one skilled in the art to which this invention relates, during the extensive manufacture of the same, and I, therefore, reserve the right to make such alterations or changes as shall fairly fall within the scope of the appended claim.

What I claim is:

A pipe provided with a bowl, a stem extending from said bowl, said stem provided with a passage, a substantially cup-shaped casing having a flat bottom, said cup-shaped casing being disposed in the bottom of said bowl, said cup-shaped casing

provided with a side opening in communication with said passage, a shaft slidably mounted in the bottom of said casing, a disc grip secured to the outer end of said shaft, a head provided with a rounded top and a flat bottom fixedly secured to the inner end of said shaft, said head having a cross-sectional area substantially corresponding to the transverse cross-sectional area of the interior of the casing and sliding upon the inner wall of said cup-shaped casing, said head having its flat bottom normally resting against the flat bottom of said cup-shaped casing, and said head being adapted to move above said side opening of the casing and into the bowl with its top surface above the casing, whereby a vaulted condition of tobacco in the bowl can be formed.

LINCOLN T. YOUNG.
